Edmund R. Angell.

UNITED STATES PATENT OFFICE.

EDMUND R. ANGELL, OF DERRY, NEW HAMPSHIRE.

CONDENSER FOR GAS APPARATUS.

1,020,339.

Specification of Letters Patent. Patented Mar. 12, 1912.

Application filed September 13, 1905. Serial No. 278,336.

To all whom it may concern:

Be it known that I, EDMUND R. ANGELL, a citizen of the United States, residing at Derry, in the county of Rockingham and 5 State of New Hampshire, have invented a new and Improved Condenser for Gas Apparatus, of which the following is a specification.

The object of my invention is the construction of a chamber in gas apparatus for 10 cooling the gas and removing moisture and other condensable fluids therefrom before it enters the gasholder, the chamber to be so located as to utilize the cooling power of the 15 liquid in the gasholder seal and at the same time keep the whole device most compact. It also provides means for removing the condensation and for further drying and filtering the gas before it comes to the burners. I 20 accomplish these things in the following manner.

The figure is a sectional elevation of the device, and the letters represent the corresponding parts to which they refer.

25 A and B represent two concentrically located tanks or cylinders and C the gasholder floating in liquid in the annular space X between them.

C C is the condensing chamber, occupying 30 the space within the cylinder B, the roof E and floor D. The floor D is in the shape of an inverted cone. It extends outwardly from the bottom of the chamber, forming the bottom also of the annular space X and 35 is attached at its circumference to the cylinder A.

E represents the inverted cone-shaped cover over the chamber C C, and F is the broad flange of the cover shutting into the 40 gasholder seal within the annular space to seal the gasholder from the chamber. This cover is removable so as to provide access to the interior of the chamber.

G represents a pipe extending from the 45 central lowest part of the cover E obliquely downward to the side and near the bottom of the chamber and is open throughout. The top L of the gasholder is made in the shape of an inverted cone for the purpose of securing firmness and for securely supporting weights necessary to give the required gas pressure.

The guides of the gasholder may be of the 50 ordinary construction consisting of grooved pulleys R R attached to opposite sides of the top of the gasholder and rolling against up-

right rods S S fastened to the outer tank A, or other suitable method of guiding may be used.

H represents a pipe of large diameter, attached to the central lowest part of the bottom D and extending to the trap N just outside the tank A. 60

P is a draw-off in the trap N and O is a stop-cock in the pipe extension from the trap 65 to the source of gas.

W is the extension of the cylinder A below the floor D and serves only as a base and support for the machine.

J is the gas outlet pipe from the gas 70 holder. It is fastened in the roof E by the lock-nuts y, and in the cylinder A by lock-nuts z. It is provided with the stop-cock 2 and enters the chamber A'. This chamber combines the trap K in its lower 75 part.

U is a draw-off in the trap.

S' represents the service pipe placed near the top of this chamber.

C' represents a nipple and cap for opening and closing the chamber. Drying material is placed upon the sieve B', and cotton, or other straining substance, fills the upper part of the chamber. The use of these things is obvious. 80

I is a pointer hanging from the top of the gas holder and working over a scale on the tank A, to index the quantity of gas in the holder. T is an arm also fastened to the top of the gasholder and adapted to engage 85 mechanism connected with the gas-generating appliance. 90

M is a cover and protection for the gasholder. It is supported by arms V V fastened to the tank A. 95

As the warm gas loaded with moisture enters the chamber C C through the pipe H it tends to rise to the roof E. This forces the cooler gas at the bottom of the chamber up into the gasholder through the oblique 100 pipe G, while the moisture, coming against the cool sides of the chamber, runs down into the pipe H and trap N, from which it may be removed through the draw-off P, after complete condensation occurs. 105

Having thus fully described my invention, I claim as new and desire to secure by Letters Patent the following:—

1. A condensing chamber in the gas passage from its source to the gasholder, 110 formed by the inner cylindrical wall of the gasholder seal, a tunnel shaped cover with

a broad flange shutting into the gasholder seal, and a tunnel shaped floor at the bottom of said wall, receiving the entry of gas near its central lowest point, in combination with 5 the gas channel from the condensing chamber to the gasholder, consisting of a pipe open throughout, extending from the central lowest point of the roof, obliquely downward with its lower end at the side and 10 and near the floor of said condensing chamber.

2. A condensing chamber in gas apparatus, in the gas passage from its source to gasholder, formed by the inner cylindrical 15 wall of the gasholder seal, a tunnel shaped cover with a broad flange shutting into the seal of the gasholder, and a tunnel shaped floor receiving near its central lowest point the gas entry pipe connected with a drip 20 pocket and means for removing the con-

denser therefrom, in combination with the gas channel from the condensing chamber to the gasholder, consisting of a pipe open throughout, extending from the central lowest point of the roof obliquely downward with its lower end at the side and 25 near the floor of said condensing chamber.

3. In gas apparatus, the combination of a gasholder floating in an annular space, a chamber within the inner wall of said annular space, a gas channel entering near the central lowest point of the floor of said chamber and continued from the side near the floor to the central lowest part of the roof thereof.

EDMUND R. ANGELL.
